(57) **CLAIM**

The ornamental design for a light fixture, as shown and described.

DESCRIPTION

FIG. 1 is a perspective view of a first embodiment of a light fixture in accordance with my new design;

FIG. 2 is a bottom plan view of the first embodiment of the light fixture in accordance with my new design, the top plan view being identical thereto;

FIG. 3 is a front elevation view of the first embodiment of the light fixture in accordance with my new design, the rear elevation view being identical thereto;

FIG. 4 is a side elevation view of the first embodiment of the light fixture in accordance with my new design, the opposite side being identical thereto;

FIG. 5 is a perspective view of a second embodiment of a light fixture in accordance with my new design;

FIG. 6 is a front elevation view of the second embodiment of the light fixture in accordance to my new design, the rear elevation view being identical thereto;

FIG. 7 is a side elevation view of the second embodiment of the light fixture in accordance with my new design, the opposite side being identical thereto;

FIG. 8 is a top plan view of the second embodiment of the light fixture in accordance with my new design; and,

FIG. 9 is a bottom plan view of the second embodiment of the light fixture in accordance with my new design.

The broken-line disclosure of elements is understood to represent portions of the article in which the design is embodied, but which form no part of the claimed design.
